FIG. 3.

UNITED STATES PATENT OFFICE.

GUSTAVE E. MEYER, OF NEW MEADOWS, IDAHO.

LEAF TURNER.

Application filed April 16, 1926. Serial No. 102,547.

This invention relates to leaf turners whereby the leaves of a musical composition may be rapidly turned without requiring a stoppage in the rendition of the composition. The primary object of the invention is to provide means whereby the leaves may be returned to the normal or initial position in the event that a part of the composition is to be repeated, and a further object of the invention is to provide means for holding the leaves of a musical composition against displacement by possible air currents which mechanism may be adjusted to the heights of various music sheets or leaves. The invention is illustrated in the accompanying drawings and will be hereinafter fully set forth.

In the drawings:

Figure 1 is a front elevation of a leaf turner embodying my present improvements;

Fig. 2 is a rear elevation of the same;

Fig. 3 is a top plan view thereof;

Fig. 4 is an enlarged detail bottom plan view with parts in section on the line 4—4 of Fig. 1;

Fig. 5 is an enlarged detail section on the line 5—5 of Fig. 1;

Fig. 6 is an enlarged detail section on the line 6—6 of Fig. 1;

Fig. 7 is an enlarged detail on the line 7—7 of Fig. 1.

In carrying out the invention, there is provided a base plate 1 which is adapted to be clamped to the rail 2 of a piano desk or may form a part of a music stand. In the present drawings, I have shown a clamping element 3 adapted to engage the rail 2 and be secured by a set screw 4, a tongue or hook 5 being provided at the front end of the clamp to support the base plate and the parts carried thereby. At the back of the base plate 1 is a back plate 6 against which the lower portions of the sheets of music or back of a book may rest while being supported on the base plate 1. Secured to this back plate 6 and rising therefrom near the ends thereof are standards 7 which may conveniently be flat bars fitted at their lower ends in sockets 8 on the rear of the back plate 6 and having their upper ends engaged through keepers or sleeves 9 at the ends of an upper bar 10 which is thereby held to the standards and may be shifted

vertically relative thereto. The hooks 5 engage in the lower ends of the sockets 8, as shown in Fig. 7. The bar 10 is constructed with notches or openings 11 in its end edges to permit access to the lower free ends of latches 12 which may conveniently be resilient plates secured at their upper ends upon the bar 10 and having their lower free ends projecting downwardly beyond the upper walls of the said openings or notches 11, as shown in Figs. 1 and 6. Near their lower ends, the latches 12 carry lugs or pins 13 which are adapted to project through openings 14 provided therefor in the bar 10 and engage in a selected one of a series of sockets 15 provided in the front side of the respectively adjacent standards 7. The bar 10 may thus be set at any desired height from the base plate 1 and back plate 6 and the device thereby adjusted to accommodate music leaves or sheets of various vertical dimensions.

Upon the front side of the top bar or plate 10 at the center thereof is secured a pintle or post 16, the accompanying drawings showing said post as being fitted in brackets or supporting plates 17 at its upper and lower ends whereby it will be held in spaced relation to the top plate or bar. Rotatably mounted upon the post or pintle 16 are a plurality of leaf turning arms 18 and associated with the post and each turning arm is a spring 19 having its ends engaged with the bar 10 and with the respective turning arm with its intermediate portion coiled around the post or pintle so that, when the arm is swung to the right in Fig. 1, the respective spring will be placed under tension and will tend constantly to move the arm to the opposite side of the device. To hold the turning arms 18 at the right side of the device, as will be necessary ordinarily at the start of a rendition, I provide a plurality of hooks 20 which are pivotally mounted upon the bar 10 and extend rearwardly through openings 21 provided therefor in the bar, as will be understood upon reference to Fig. 5. These hooks are of graduated length, as shown clearly in Fig. 5, and are each adapted to engage over a lug or projection 22 on the upper side of the respective turning arm so that the arm will be held against movement, as shown in Fig. 5. To the rear ends of the several hooks 20 are attached the upper ends

of connecting rods 23 which have their lower ends engaged with the outer ends of cranks 24 on the rear ends of rock shafts 25 which are journaled on the under side of the base plate 1 and are equipped at their front ends with handle levers 26. These rock shafts 25 are held to the base plate 1 by bearing brackets or keepers 27 of any approved type and upon each shaft, adjacent the respective brackets, I provide lugs or projections 28 which, by engaging the sides of the bearing brackets, prevent endwise movement of the shafts and by bearing against the under side of the base plate limit the rocking movement of the shafts so that the respective handle members 26 will always be in the proper position to be easily manipulated by the performer. It will be understood that, when any one shaft 25 is rocked so as to exert a downward pull upon the corresponding pitman 23, the hook 20 connected with said pitman will be rocked so that it will release the lug 22 engaged thereby and the corresponding turning arm will then be swung to the left under the influence of the attached spring 19. In order that the latch hook 20 may be returned to its operative position and normally held in that position, I provide contractile springs 29 which are attached at their opposite ends to the back plate 6 of the supporting structure and to extensions of the pivot pins connecting the cranks 24 to the respective pitmen 23, as shown in Fig. 2. These springs will be placed under tension when the respective handle member 6 is rocked and when the pressure upon the handle is released the spring will at once contract so as to return the hook to its working position. In order that the pitmen may be readily set to correspond to the height of the upper bar 10, they are telescopic or extensible in construction with one member fitting within the alined hollow member and secured in set relation by thumb screws 30, as will be understood upon reference to Figs. 1 and 2.

Referring particularly to Fig. 1, it will be noted that the pivotal end of each turning arm is in the form of a yoke 31 spanning the several springs 19, this construction providing a wide support for the respective arms so that they will not be apt to sag in use. Carried by the upper side of each yoke 31 are a pair of spaced arms 32 which project forwardly from the yoke in divergent relation and one of which is constructed at its end to facilitate the attachment thereto of a cable 33. The other arm 32 is formed at its front free end with an arcuate guide or shoe 34 over which the respective cable 33 may pass and by which the cable will be supported, the cable being thus so disposed that a pull exerted upon the cable will be transmitted to the turning arm in the proper manner to easily and

effectually swing the same about the supporting post or pintle 16. Adjacent the upper end of the pintle 16, a notch 35 is formed in the upper edge of the frame bar 10 and in this notch are mounted grooved idle rollers 36 or pulleys about which the respective cables 33 pass so that they will be properly supported and guided to always be in operative relation to the respective turning arms. The idlers or guide rollers are supported and separated by horizontal partitions 361 which also separate the cables and prevent them becoming entangled. At the back of the frame bar 10, the cables 33 are carried to the left of the guide pulleys 36 and each cable is attached at its end to the upper end of a bell crank or angle lever 37, the several bell cranks or angle levers having a common fulcrum 38 and each also having connected thereto the upper end of a pitman 39. The several bell cranks or angle levers are held to the back board by a retaining loop or guide bracket 40 which is secured at its ends to the said board and extends over all the bell cranks whereby they will be maintained in upright operative position. The pitmen 39 are telescopic in construction in the same manner that the first described pitman 23 are constructed, and the lower ends of the several pitmen 39 are pivotally connected to the upper ends of cranks 41 at the rear ends of rock shafts 42 which are mounted on the under side of the base plate 1 and correspond in form and arrangement to the rock shafts 25, as will be understood upon reference to Fig. 4. Each rock shaft 42 is equipped at its front end with a handle member 43 which may be of any suitable approved form.

Each turing arm 18 carries a clamp 44' which is adapted to engage the upper edge or the side edge of a sheet of music so that, when the arm is swung from one side to the other side of the device, the sheet of music will be turned. These clasps 44' may be of various lengths accordingly as they are designed to engage the top edge or the side edge of a leaf and they may, of course, be disposed at the extreme ends or at intermediate points in the length of the respective turning arms. One of these clasps may also be provided adjacent the post 16 to engage the inner edge of a single sheet. I also provide holding rods 45 which are carried by the upper frame bar 10 and are adapted to engage over the backs of a music book so that the books will be held close to the supporting frame and thereby prevented from prematurely causing a leaf to turn. The leaf-engaging jaws of the several clasps 44' may be of any desired form. I prefer a disk of felt or analogous material, as shown at 46, to avoid mutilation of the leaf.

In many styles of pianos, the upper ends of the standards 7 may be engaged behind

a molding strip on the top of the piano to be held against falling forward. With other makes of pianos, a clip 47 may be employed, such clip consisting of a shank 48 having lateral resilient fingers 49 and a loop 50 which also serves as a handle. The shank is disposed across the upper ends of the standard and the desk 51 below the top 52, the desk and standard being clasped by 10 the fingers, as shown in Fig. 6.

My device is exceedingly compact and simple in the construction and arrangement of its parts and will be found highly efficient in use. The device will be very advantageous in outdoor renditions inasmuch as it will 15 effectually hold the leaves of a musical composition so that they will not be blown away and lost in the wind and the leaves may be readily turned without requiring any cessation in the playing. A single leaf or sheet may be returned to the right side of the device by manipulation of the proper rock shaft 42 or, by rocking the shaft connected 20 with the innermost arm, all of the arms and, consequently, all the leaves of the composition may be at once returned to the right side of the device. It will be noted that I have illustrated three turning arms. This 25 number, however, is merely illustrative and any desired number of arms may be provided. Very often one arm will be sufficient and the leaf turner will be furnished in such 30 sizes and with such numbers of arms as any customers may prefer.

Having thus described the invention, I claim:

1. In a leaf turner, the combination of a leaf-supporting base, an upper frame bar supported above the said base, leaf-turning arms pivotally mounted upon the upper frame bar, and means for controlling said arms including forwardly projecting rock shafts operatively connected with the respective arms and mounted in bearings on the under side of the base and each provided with stop lugs arranged at the inner ends of the bearings and adapted to impinge against the base whereby to prevent endwise movement and limit the rocking movement of the shaft. 50

2. In a leaf turner, the combination of a supporting frame, turning arms mounted upon the frame, cranks on the back of the frame, guide pulleys at the top of the frame, means operable from the base of the frame 55 for actuating said cranks, diverging projections on the several turning arms, and flexible connections between the cranks and the arms whereby to swing the arms from left to right, said flexible connections being trained around the guide pulleys and each secured at one end to one of the projections on the respective arm and having its portion adjacent said end passing across and supported by the other projection. 60 65

In testimony whereof I affix my signature.

GUSTAVE E. MEYER. [L. S.]
